LOCK

Allan R. MacLagan, Western Springs, Ill., assignor to Western Electric Company, Incorporated, New York, N. Y., a corporation of New York

Application October 10, 1936, Serial No. 104,987

8 Claims. (Cl. 70—355)

This invention relates to locks, and more particularly to rotor center tumbler type locks for telephone pay station equipment.

It is an object of the invention to produce a 5 cheaper, simpler and more theft-proof lock.

In accordance with one embodiment of the invention a lock provided with movable and fixed tumblers has a barrel or center made up of three 10 separate parts, one of which acts as an actuator for the bolt of the lock, the second one of which nests in the actuator and drives it when a key of proper contour is inserted through the third part of the center which serves to rotatably support the lock center in the case, and prevent the 15 insertion of keys not properly grooved. The bolt actuator element of the lock center or barrel nests in a depression formed in the base of the lock case, and the part which fits into the actuator has an extending edge which clamps a flat portion 20 of the bolt of the lock against the base of the lock case. The bolt of the lock comprises a flat plate corrugated at one end to provide a strong latching portion and has slots formed 25 therein for cooperation with the pins which serve to hold the cover and base together to guide the bolt in its movement to and from latching position.

A complete understanding of the invention may be had by reference to the following description considered in conjunction with the accompanying drawing, wherein

Fig. 1 is a perspective view of a lock embodying the preferred form of the invention, the cover plate being removed to show more clearly the 30 operating parts of the lock and the lock center being shown rotated to a position where the actuator is just beginning to cam the bolt out of latching position;

Fig. 2 is an exploded view of the lock, the relative positions of the parts being the same as in Fig. 1;

Fig. 3 is a sectional view taken substantially along a line extending through the center of the barrel of the lock with the lock center rotated to a position at right angles to its normal position and the bolt partly retracted;

Fig. 4 is a fragmentary sectional view taken along the line 4—4 of Fig. 3 in the direction of the arrows;

Fig. 5 is a fragmentary sectional view taken along the line 5—5 of Fig. 4 in the direction of the arrows, and

Fig. 6 is a fragmentary sectional view taken along the line 6—6 of Fig. 3 in the direction of the arrows.

Referring now to the drawing wherein like reference characters designate the same parts throughout the several views, a lock case constituting a preferred embodiment of the invention 55 comprises a base 10 and a cover 11. The base 10

is provided with mounting lugs 12—12 whereby the lock, after being assembled, may be mounted. The base 10 has a portion thereof bent over as shown at 13 to form one of the ends of the lock case, and to form a guide for a bolt 14 slidable in 5 the lock case. The latching portion of the bolt 14 is corrugated as indicated at 15 to strengthen it, and the bent over portion 13 of the base 10 has an irregular slot 16 formed therein which corresponds in configuration to the corrugations 10 formed in the bolt.

Approximately midway between the upper and lower edges of the casing a circular depression 17 is formed therein for receiving a bolt actuator 18. The bolt actuator 18 is formed from a flat strip of 15 metal and is punched with a rectangular opening 19 formed therein. The actuator 18, the body portion of which is substantially circular in shape to fit the circular depression 17, has an extending portion formed thereon which extends from the 20 circular body of the actuator and which is bent out of the plane of the body portion and forms an actuating arm 20 for moving the bolt 14 to and from latching position. As shown in Fig. 3, the actuator 18 has its circular body portion positioned within the circular depression 17 in the base, and the arm 20 extends into an aperture 21 25 formed in the bolt.

In the assembled lock a center portion 25 has a pair of extending portions 26 which fit into the rectangular opening 19 formed in the actuator 18. The center portion 25 of the barrel of the lock is made of a flat sheet of metal punched to provide the pair of extending portions 26, and a pair of slots 27, and then folded to a U-shaped 30 configuration, as clearly shown in Fig. 2. There are associated with the center portion 25 four tumblers 28, 29, 30 and 31. Three of these tumblers, that is, the ones designated 28, 29 and 31 are pivotally mounted upon a pin 32 secured to the base 10. The tumbler 30 is not pivotally 35 mounted, but is held stationary being supported by the pin 32 and a second pin 33 also mounted upon the base 10. The tumblers 28, 29 and 31 have flat springs 34, 35 and 36, respectively, secured thereto. These springs 34, 35 and 36 engage the pin 33 and normally tend to rock their associated tumblers in an anti-clockwise direction about the pivot pin 32. The upper faces (Fig. 2) of the tumblers 28, 29 and 31 are slotted 40 as shown at 37, 38 and 39, respectively, the slots being spaced predetermined distances from the left edges (Fig. 2) of the tumblers. The slots 37, 38 and 39 must all be brought into direct alignment by turning a properly formed key in the 45 lock before the bolt 10 can be withdrawn.

Mounted upon the bolt 14 and staked in an aperture 45 therein is a stop member 46 which will move into the slots 37, 38 and 39 when they are aligned by a proper key, but which will pre- 50

- vent the retraction of the bolt when a key having improper cuttings is turned in the lock due to its engagement with the upper portions of one or more of the movable tumblers 28, 29 and 31.
- 5 A relatively shallow depression 44 is formed in the base 10 in which the upset portion of the stop member 46 will move when the bolt is moved. The fixed tumbler 30 has an irregular face 47 which conforms to the fluting of a key designed 10 for the lock, and the fixed tumbler is so positioned as to extend between the edges of the slots 27 in the center portion 25 when the center is rotated by the proper key.

The cover 11 is made of sheet metal and comprises a front portion 50, sides 51 and 52 and a bottom 53. The sides 51 and 52 are provided with extending lugs 54 and 55, respectively, staked or riveted in slots 56 and 57 formed in the base 10, and three apertures 61, 62 and 63 are 20 formed in the front portion. The apertures 61 and 62 receive the ends of the pins 32 and 33, respectively, when the lock is assembled, and after the lock is assembled the pins may be upset to rivet the lock cover 11 in place on the base 10. The third aperture 63 is adapted to receive a lock center cap designated generally by the numeral 64 which comprises a tubular portion 65 having a shoulder 66 formed on one end thereof and having an end 67 formed integral therewith. The center cap 64 is adapted to engage the front or right end (Figs. 1, 2 and 3) of the center portion 25, is adapted to be staked thereon as shown at 68, and is provided with a grooved slot 69 in the end 67 corresponding in 35 configuration to the fluting in the sides of a key. The tubular portion 65 of the cap 64 extends through the aperture 63 and the shoulder 66 bears on the inner surface of the cover 11, thereby accurately positioning the cap and the center portion and holding all of the assembled parts 40 in position in the lock. The right end (Fig. 3) of the center portion 25 will engage the portion 67 of the cap, and at the left end (Fig. 3) a shoulder 70 formed on the center portion 25 will engage the right hand surface of the bolt 14 along the edge 71 of the aperture 21. In this 45 manner the bolt will be held in close engagement with the base 10 and any attempt to force the lock by manipulating the bolt in a direction transverse to its normal direction of movement 50 will be frustrated.

Although a specific embodiment of the invention has been described hereinbefore, it will be understood that the invention is subject to many 55 modifications without departing from the scope of the appended claims.

What is claimed is:

1. A lock for telephone pay station equipment comprising a bolt movable to and from latching position and having a flat portion formed to provide cam surfaces and a portion corrugated to provide a thickened and strengthened latching portion, said corrugations extending in a direction parallel to the direction of movement of the bolt and some of them also extending at an angle to the direction of the movement of the bolt, an actuator having a portion extending to engage said cam surfaces, and means for controlling the operation of said actuator including a center cap slotted to receive a key, a center for engaging said actuator and cap, and a plurality of tumblers positioned in the path of a key between the cap and actuator.

2. In a lock for telephone pay station equipment, key operated tumblers, a bolt controlled by the tumblers, an oscillatable bolt actuator having a portion thereof in a plane parallel to said bolt and an actuating portion in the plane of said bolt, said portion in the plane parallel to the plane of the bolt having a rectangular opening therein, and a key guide extending into said opening.

3. In a lock for telephone pay station equipment, key operated tumblers, a bolt controlled by the tumblers, an oscillatable bolt actuator having a rectangular opening therein, and a key guide having portions thereof extending into the opening of the actuator and having a shoulder 10 for engaging a surface of the bolt to hold the 15 bolt in a predetermined plane.

4. In a lock for telephone pay station equipment having a case, movable and fixed tumblers, and a retractable bolt, a center formed in three 20 parts comprising a bolt actuator oscillatable in a plane parallel to the plane of movement of the bolt and having a portion thereof extending into the plane of the bolt for actuating it, a key guide having a portion thereof extending into 25 operating relation with said actuator and a shoulder engaging the bolt to hold it in a pre-determined plane, and a cap mounted on the key guide and oscillatable in an aperture in said case, said cap being provided with a shoulder 30 portion for engaging the case to hold the key guide in a predetermined position.

5. In a lock for telephone pay station equipment, a case for enclosing lock parts, key actuatable tumblers, a bolt controlled by said tumblers, 35 a bolt actuator oscillatable in said case and having a rectangular opening therein, a key guide having portions thereof extending into said opening, and a key cap having an irregular slot for receiving a key of predetermined configuration 40 assembled on the key guide and oscillatable in the casing.

6. A lock for telephone pay station equipment comprising a lock center for receiving a key, a plurality of key actuatable tumblers, a bolt 45 actuator movable by the proper key, and a bolt for actuation by the actuator comprising a sheet of metal having corrugations formed therein to thicken and strengthen it and having a flat portion in the plane of the said corrugations extending in a direction parallel to the direction of movement of the bolt and some of them also extending at an angle to the direction of movement of the bolt.

7. A lock comprising a casing, a bolt, and 55 means within the casing for actuating the bolt, the extending portion of the bolt having corrugations extending in the direction of movement thereof and the wall of the casing having a slot of the same configuration as a cross-section of 60 the corrugated bolt, the bolt being mounted for reciprocation in said slot, some of the corrugations in said bolt also being formed at an angle to the direction of movement of the bolt to strengthen it.

8. A lock comprising a casing, a bolt, and means within the casing for actuating the bolt, said bolt having corrugations extending in the direction of movement thereof, some of said corrugations also extending at an angle to the direction 70 of movement of the bolt.

CERTIFICATE OF CORRECTION.

Patent No. 2,134,368.

October 25, 1938.

ALLAN R. MacLAGAN.

It is hereby certified that error appears in the printed specification of the above numbered patent requiring correction as follows: Page 2, second column, line 50, claim 6, before the word "said" insert actuator; and that the said Letters Patent should be read with this correction therein that the same may conform to the record of the case in the Patent Office.

Signed and sealed this 10th day of January, A. D. 1939.
